CLAIM

The ornamental design for an edible pet chew, as shown and described.

DESCRIPTION

FIG. 1 is an upper front perspective view of an edible pet chew showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-4 and 6-7 illustrate portions of the edible pet chew that form no part of the claimed design.
